UNITED STATES PATENT OFFICE.

CHESTER C. SMALL, OF NEWTON, MASSACHUSETTS, ASSIGNOR TO UNITED SHOE MACHINERY COMPANY, OF PATERSON, NEW JERSEY, A CORPORATION OF NEW JERSEY.

METHOD OF PREPARING SOLES FOR BOOTS OR SHOES.

1,061,416.

Specification of Letters Patent.

Patented May 13, 1913.

Application filed February 12, 1913. Serial No. 747,951.

To all whom it may concern:

Be it known that I, CHESTER C. SMALL, a citizen of the United States, residing at Newton, in the county of Middlesex and State of Massachusetts, have invented certain Improvements in Methods of Preparing Soles for Boots or Shoes, of which the following description, in connection with the accompanying drawings, is a specification, like reference characters on the drawings indicating like parts in the several figures.

Although efforts have been made heretofore to improve soles for boots and shoes by subjecting them to great pressure, in order to compress and condense them in a manner similar to that in which top lifts are condensed, such attempts have been unsuccessful commercially because the article produced was substantially thinner than the original blank. The reduction in thickness in the interior of the sole is of no consequence, but the substantial and symmetrical appearance of a shoe depends to a large extent upon the thickness of the sole at its edges so that any sacrifice of thickness at the edges, such as is involved in the compression of articles of sole leather as heretofore practised, is not permissible. So conspicuously important is this matter of the thickness of the sole edges that it has always been the practice to gage soles of a given quality, and to determine their commercial value, entirely by the thickness of the edges in the forepart. This thickness of the edges is measured in "irons"; a difference in thickness of one "iron," *i. e.* $\frac{1}{8}$ of an inch, between two soles of medium size and quality, represents a difference in market value of from three to four cents a pair.

I have discovered a method by which, for the first time, it is possible to impart to soles the many advantages secured by compressing, without any attendant disadvantages. By this method pressure is applied to the faces of a sole blank in such manner that the interior wear resisting portion of the blank receives the maximum amount of pressure, which is preferably sufficient to condense and harden that portion of the sole and, in the manner of practising the method hereinafter described, to reduce it somewhat in thickness; while substantial reduction, or any reduction, in the thickness of the edges

is avoided. I prefer so to apply the pressure as to form a marginal portion thicker than the interior and of substantial width, so that there may be cut from blanks of one shape soles of a variety of contours all having marginal portions thicker than their interior portions and preferably of such width that channels may be formed in said thicker marginal portions. I also contemplate making the thick marginal portion wider at the part where the greatest variation in the shapes of the soles is likely to occur. This is usually at the toe.

In the preferred manner of practising the invention the pressure which is exerted upon the marginal portion is progressively less from the outer boundary of the interior portion toward the edge of the sole, where the reduction in thickness, if any, is negligible, and the pressure is applied in such manner that the face of the grain side of the compressed sole, and preferably also the face of the flesh side, is smooth and unbroken by any shoulder or sharp line of demarcation between the interior and marginal portions. Preferably also the edges of the sole blank are confined during the application of pressure to its faces and this prevents spreading of the sole by the pressure exerted upon its faces and contributes generally to the efficacy of the method. To secure the best results I prefer, as steps in the method, to upset the stock at the edges of the sole and to mold the upset stock by the pressure exerted upon the faces of the marginal portion.

It should be understood that in the practice of my invention pressure may be applied to the faces of a sole throughout their entire areas or, if desired, pressure may be exerted upon only a part of the sole as, for example, the forepart. When compressing a part only, it is preferable so to apply the pressure that the faces of the compressed portion shall merge gradually into the faces of the uncompressed portion, thereby avoiding an abrupt shoulder or any noticeable line of demarcation, which would be particularly objectionable on the grain side of the sole.

The sole produced by my method, when practised in the preferred manner, has in its interior wear receiving portion all the advantages imparted by great pressure and its

marginal portion has received sufficient pressure to improve it materially while the thickness of the edge is not reduced substantially, if at all; and the faces of the interior and marginal portions are substantially continuous and smooth so that the difference in thickness is not noticeable. I prefer in the practice of my method to perform all the steps necessary or useful to produce such a product but it should be understood that one or more of the steps may be omitted without departing from the invention, the scope of which is limited only as defined in the claims.

15 The improved sole which is produced by the practice of my novel method is not herein claimed but is made the subject-matter of my pending application for Letters Patent of the United States, Serial No. 732,703, filed November 21, 1912.

20 In the drawings:—Figure 1 is a perspective view of a sole blank cut from a poor grade of leather which may be transformed into an improved sole by the method constituting the present invention; Fig. 2 is a perspective view of a sole after it has been improved by this method; Fig. 3 is a perspective view showing a mold comprising dies which may be employed in carrying out the method. The dies are shown in initial open position; Fig. 4 is a sectional view of the mold taken in the plane 4—4 of Fig. 3, showing upon a larger scale by dotted lines the sole blank before it has been compressed 25 and by full lines the dies and the blank in their relative positions at the time of final compression; Fig. 5 is a view similar to Fig. 2 showing the sole produced by a modification of the method; and Fig. 6 is a view similar to Fig. 3 showing dies suitable for carrying out the modified method.

25 A sole blank which may be greatly improved by treating it in accordance with my novel method is shown in Fig. 1. While the advantages of the method are by no means limited to its practice upon sole blanks of the poorer grades of leather, the improvement effected by it is more striking in that class of work and I have accordingly shown 30 in that figure a sole blank of a very poor grade of leather which is warped, defaced on its grain side, of uneven thickness at its edges and otherwise unsatisfactory for use as a sole. Such leather frequently has soft 35 or thin spots which may be found in the middle of a sole where the greatest wear occurs. The soft or thin parts absorb water readily and the grain surface of the leather is often so uneven and rough that the grain 40 will be cut through when the sole is buffed.

45 In the practice of my method I find it desirable to put the sole blanks somewhat in temper before subjecting them to pressure and I preferably prepare the blanks by sprinkling them with water and then piling

them up and allowing them to stand for some hours.

50 In Figs. 3 and 4 of the drawings is shown a mold comprising face and edge dies which I have used in the practice of my method. Fig. 3 shows the mold open. In using it to practise my method the sole is placed on the lower face die 8, the edge dies 4 and 6 are moved toward the die 8 and finally the upper face die 10 is moved toward the die 8. 55 In order to secure the desired amount of pressure the dies are preferably used in a powerful compressing machine and the machine which I have specially designed for this purpose is capable of applying to a sole 60 a pressure of 500 tons. In order to maintain the thickness of the edges of the blank the marginal portion of at least one of the face dies should be cut away. Preferably the face of the marginal portion 12 should 65 merge gradually into the face of the interior portion of the die and I prefer also to bevel both of the face dies in this manner, as shown in the drawings. The depth of the bevel at the extreme edge measured from the 70 plane of the flat interior portion is approximately 0.12 of an inch on each die and the width of the beveled margin varies from $\frac{5}{8}$ of an inch to $1\frac{1}{4}$ inches. The margin is made of substantial width in order that the sole 75 produced by the method shall have an edge thicker than its interior portion after the rounding and trimming operations and the maximum width of the beveled margin of the die is so located as to furnish a thicker 80 margin of maximum width on that portion of the sole where the most stock is removed in the rounding operation. This is generally at the toe and the dies are shown as having the bevel of maximum width at the 85 toe portions.

90 It is desirable to cut the sole blank slightly larger than the mold around the forepart, as shown by dotted lines 9 in Fig. 4. It is my practice to cut the sole about $\frac{3}{2}$ of an 95 inch larger all around the forepart, this excess of size being gradually reduced along the shank and disappearing at the wide part of the heel seat. This excess material is forced inwardly by the side dies and is 100 molded by the face dies, thus contributing 105 to the securing of the desired thickness in the marginal portion of the blank.

110 Referring to Fig. 3, it will be noted that 115 since the edge dies in closing move directly toward each other, they will in this type of mold exert practically no inward pressure upon the edges of the blank adjacent to their inner corners 5, 7 and thus do not provide in that region any upset edge material 120 to be molded into the margin. I find, however, that in the sole produced by my method the edge of the marginal portion of the toe 125 has substantially the same density as the marginal edges on the sides and experiments 130

have shown that under the very heavy pressure exerted by the face dies the stock in the forepart in the region indicated by the arrows in Fig. 3 is forced toward the toe, 5 thus contributing stock from that region to the thicker margin at the toe. While this movement of the stock is slight, it is usually discernible and seems to contribute materially to the desired result at the toe.

10 The amount of pressure which is required in the practice of my method varies considerably according to the condition and quality of the stock and the size of the sole blank. In order to obtain all the advantages secured by practising the method in the preferred manner the pressure should be sufficient to render the interior portion of the sole very hard and dense, to make the marginal portion firm and to impart a smooth, 20 hard surface to the entire grain side of the sole. An operator quickly learns to determine from the appearance of the compressed blank whether sufficient pressure is being applied.

25 The preferred manner of practising the invention is illustrated in Fig. 4 in which the outline of the original blank is indicated by dotted lines and the product of the method is shown in section in the closed molds. It 30 will be observed that the greatest pressure is exerted upon the interior portion of the sole, while, owing to the beveled margins on the face dies, the pressure exerted upon the margin of the sole is progressively less from the 35 boundary of the interior portion toward the edge of the sole where the thickness of the product is shown as substantially the same as that of the original blank. In Fig. 2 is represented the sole produced by treatment, 40 according to my method, of the sole shown in Fig. 1. The wide margin is indicated by shading which shows the maximum width at the toe. In the rounding operation a variety of shapes of soles may be cut from 45 this blank, one of these shapes being indicated by the broken line 16 and it will be observed that when the sole is rounded on this line there will still be left a margin of substantial width and of greater thickness 50 than the interior portion. The margin left after the rounding operation will usually be wide enough so that the channel formed to receive the thread or other sole fastening means will be within the margin. This is 55 of advantage because it is necessary that the portions of the sole operated upon be thoroughly tempered for the rounding and channelling operations and as the margin of the sole is less dense than the interior it will absorb water more readily.

60 I prefer so to practise my method as to improve the entire sole or at least all of it which is to be visible in the finished shoe, including the shank, but it may be desired to 65 treat the forepart only, since the shank por-

tion receives practically no wear and the heel seat portion is covered by the heel. Dies adapted for applying pressure in accordance with my method to the forepart only are shown in Fig. 6 and a sole compressed by these dies is shown in Fig. 5. When the forepart only is compressed, it is 70 desirable that the operation shall be so performed as not to form a line or ridge in the region between the compressed and uncomplicated portions and this is especially important as regards the grain side of the sole. It is preferable, therefore, when practising the method in this manner, so to apply pressure as to merge gradually the surfaces of 75 the uncompressed and compressed portions of the sole. I have accomplished this by using face dies 20 which are gradually beveled off at 18 so that the sole compressed by them will have the compressed face of its 80 forepart 22 and the uncompressed face of the shank portion 24 connected by the portion 26 which merges gradually into both of the said faces. The rear corners of the edge dies are also rounded at 28, 28 to prevent 85 the formation of marks upon the edges of 90 the sole.

Although in both pairs of face dies herein shown and described each die is formed with a beveled margin, it is not essential that the 95 marginal portions of both face dies be cut away, as one of the dies may be flat while the marginal portion of the other may be cut away sufficiently to secure the desired result. Advantages of having both the face dies 100 beveled, as herein illustrated, are that in their use no tendency to warp is imparted to the sole, and the same mold may be used for both rights and lefts.

While in the preferred manner of practising my method, as above set forth, very great pressure is exerted upon the interior portion of the blank, hardening and condensing it, and pressure is so exerted upon the marginal portion that the edges of the 110 compressed sole shall be of substantially the same thickness as the edges of the original blank; I desire it to be understood that it is within my invention so to apply pressure to the blank that the marginal portion will be 115 made thicker than the marginal portion of the original blank. To accomplish this, the marginal portion of one or both of the face dies may be cut away to a greater depth below the plane of the interior face than in the 120 dies above described; or, using a mold such as is herein shown and described, and cutting the sole blank slightly larger than the mold, less pressure may be exerted through the face dies, so that the edges which are upset 125 and thickened by the side dies will not receive enough face pressure to reduce them to their original thickness; or, using either of these types of face dies, the sole blanks may be cut with a greater excess width than is 130

above suggested, to afford additional stock to be upset and molded into a thicker margin.

It is my practice to cut sole blanks which are to be improved by my method of such shapes that a variety of shapes of soles may be cut from each blank in the sole rounding operation and this practice is advantageous in that it effects a great saving in the cost of the cutting dies required to die out the sole blanks and the compressing molds for treating them in accordance with my method. It should be understood, however, that my invention is not limited to compression of a sole blank before the rounding operation, and further, that the method may advantageously be practised in improving what is variously termed a "tap", "slip sole" or "half sole". The terms "sole" and "sole blank", as used in the specification and claims, should be construed accordingly.

Having explained the nature of my invention and set forth fully how it may be practised, what I claim as new and desire to secure by Letters Patent of the United States is:—

1. The method of improving sole blanks for boots or shoes which comprises applying to the faces of a blank pressure which reduces substantially the thickness of the interior portion of the blank and which reduces the thickness of the marginal portion of the blank by an amount diminishing from a maximum at the inner boundary of the margin to a negligible amount at the outer edge of the blank.

2. The method of improving sole blanks for boots or shoes which consists in forcing the edges of a blank inwardly by pressure and then, while the edges are confined, applying to the faces of the blank pressure which reduces substantially the thickness of the interior portion of the blank and which reduces the thickness of the marginal portion of the blank by an amount diminishing from a maximum at the inner boundary of the margin to a negligible amount at the outer edge of the blank.

3. The method of improving sole blanks for boots or shoes which comprises exerting thickness reducing pressure upon the faces of the interior portion of the forepart of a sole blank while confining the edges of the blank and exerting substantially less pressure upon the faces of the marginal portion between the outer boundary of the interior portion and the edge of the sole.

4. The method of preparing soles for boots or shoes which consists in confining the edges of a sole blank, exerting thickness reducing pressure upon the faces of the interior portion of the blank while the edges are held confined, and, during the operation upon the interior portion, exerting pres-

sure progressively from the outer boundary of the interior portion toward the edge of the sole.

5. The method of preparing soles for boots or shoes which consists in forcing inwardly the edges of a sole blank, applying thickness-reducing pressure to the interior portion of the blank and applying to the marginal portion of the blank pressure which is progressively less from the boundaries of said interior portion toward the edges of the blank, where it is not sufficient to reduce the thickness, thereby producing a condensed sole having its interior portion thinner than that of the original blank but having its edges of approximately the same thickness as the edges of the original blank.

6. The method of preparing soles for boots or shoes which consists in forcing inwardly the edges of a sole blank and applying to its opposite faces pressure which is greatest on the interior portion of the blank and which merges into a less degree of pressure on the marginal portion of the blank.

7. The method of preparing sole blanks for boots or shoes by subjecting them to pressure which includes upsetting the edges of the forepart of a blank and applying pressure to the faces of the forepart, including its marginal portion, in such manner as to mold the upset edge portion of the stock to produce a marginal portion thicker than the interior portion.

8. The method of preparing sole blanks for boots or shoes which comprises first upsetting the stock at the edges, and then exerting pressure on the faces of the blank while the edges are confined and thereby molding such upset stock to form a smooth marginal portion thicker than the interior portion of the blank.

9. The method of preparing soles for boots or shoes which comprises applying pressure to the faces of the forepart of a blank, including the marginal portion, while confining its edges, in such manner as to produce a sole blank having a marginal portion of greater thickness than its interior portion and of substantial width to permit shaping said sole blank by cutting it on a line lying within said thicker marginal portion.

10. The method of preparing soles for boots or shoes which comprises applying pressure to the forepart of a sole blank in such manner as to produce a sole blank having in its forepart a marginal portion of substantial width and of greater thickness than the interior portion, with the faces of said marginal and interior portions forming a substantially continuous and unbroken surface on each side of the blank, whereby said blank may be shaped by cutting it on

- a line lying within said thicker marginal portion.
11. The method of improving sole blanks for boots or shoes which comprises exerting upon the faces of a sole blank pressure which reduces substantially the thickness of the interior of the forward portion of the blank, reduces the thickness of the margin of the forward portion by an amount diminishing from a maximum at the inner boundary of the margin to a negligible amount at the outer edge of the blank, and reduces the thickness of the part of the blank connecting the thinner interior of said forward portion and the rear portion of the blank by an amount diminishing gradually from a maximum at the forward boundary of said connecting part to nothing at the rear boundary of said connecting part.
12. The method of preparing soles for boots or shoes which comprises applying pressure to the faces of the forepart of a blank, including the marginal portion, while confining its edges, in such manner as to produce a sole blank having a marginal portion of greater thickness than its interior portion and of substantial width to permit shaping said sole blank by cutting it on a line lying within said thicker marginal portion and forming a channel in said thicker 30 marginal portion.
13. The method of preparing soles for boots or shoes which comprises upsetting the side edges of a sole blank, forcing stock from the interior of the forepart of the blank toward the toe, and molding the entire margin of the forepart by pressure exerted upon its faces.
14. The method of preparing soles for boots or shoes which comprises forcing inwardly the side edges of the forepart of a sole blank, exerting upon the interior of the forepart of the blank sufficient pressure to force stock from said interior toward the toe, and progressively exerting pressure upon 45 the faces of the entire margin of the forepart from the inner boundary to the outer boundary of said margin.

In testimony whereof I have signed my name to this specification in the presence 50 of two subscribing witnesses.
